UNITED STATES PATENT OFFICE.

WILMER M. SHALLCROSS, OF MILWAUKEE, WISCONSIN, ASSIGNOR TO SHALLCROSS CONTROL SYSTEMS CO., OF MILWAUKEE, WISCONSIN, A CORPORATION OF WISCONSIN.

FURNACE.

Application filed September 15, 1921. Serial No. 500,896.

To all whom it may concern:

Be it known that I, WILMER M. SHALLCROSS, a citizen of the United States, and resident of Milwaukee, in the county of Milwaukee and State of Wisconsin, have invented new and useful Improvements in Furnaces, of which the following is a description, reference being had to the accompanying drawings, which are a part of this specification.

This invention relates to certain new and useful improvements in furnaces and refers more particularly to a regulator therefor.

In furnaces, more particularly that type employed for generating steam it is highly desirable that conditions be so regulated that each generator unit carries its share of the load under various conditions; that maximum fuel economy be obtained at all times, and that the boiler maintenance cost be maintained low.

It is, therefore, primarily an object of this invention to provide means whereby the desired regulation of the furnace is obtained.

It is more specifically an object of this invention to provide means for simultaneously actuating the flue damper and fuel feed of a furnace when the draft within the fire box exceeds a predetermined degree to automatically reduce the flue opening and decrease the volume of fuel fed the furnace, and, upon the draft falling below a predetermined degree, to increase the flue opening and volume of fuel fed the furnace.

It is another object of this invention to provide means connected with the steam head or outlet of a steam generator whereby the pressure therein will be maintained substantially constant.

A further object of this invention is to provide means for coordinating the flue damper, furnace fuel supply means, and forced draft means, whereby the furnace condition will be maintained as near as possible to the desired efficient point in order that each unit may carry its share of the load and that maximum fuel economy may be obtained and boiler maintenance cost kept at a low figure.

A still further object of this invention is to provide electrically operated means connected with the flue damper, fuel supply and forced draft means for maintaining the con-

dition of the furnace at a substantially constant point under all load conditions.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, I have illustrated one complete example of the physical embodiment of my invention constructed according to the best mode I have so far devised for the practical application of the principles thereof, and in which:

Figure 1 is a view part in section and part in elevation taken through a steam generator unit equipped with my invention;

Figure 2 is an enlarged view, part in section and part in elevation illustrating the improved pontoon switch construction which I employ for controlling the regulation of the flue damper and fuel feed means upon a change in the draft condition;

Figure 3 is a view part in section and part in elevation illustrating one of the units employed for regulating the damper flue, fuel supply means and forced draft means;

Figure 4 is an end view thereof with the motor removed, illustrating in dotted lines the limit switches which I employ;

Figure 5 is an enlarged detailed view part in section and part in elevation illustrating the means connected with the steam head or outlet for controlling the forced draft means upon the steam pressure going above or below a predetermined degree, and

Figure 6 is a diagrammatic view illustrating one of the circuits I employ in connection with my invention.

In the operation of steam generating furnaces, it is highly desirable that each unit be regulated to bear its proportionate share of the load under all conditions, be run so that maximum fuel economy will be obtained at all times and that the furnace maintenance cost be kept at a minimum amount. To obtain these desired objects, it is necessary that all the elements, essential to the efficient operation of the furnace, be coordi-

nated to perform according to the condition of the furnace and maintain the same constant under all loads.

In other words, the damper flue must be 5 opened to a greater degree when the draft within the fire box falls below a predetermined degree and at the same time the supply of fuel to the fire box must be increased proportionately with the flue damper opening 10 in order that the fire may be properly maintained, or, in the event the draft should increase beyond the desired degree, the damper must be moved toward closed position and the fuel supply proportionately decreased. The forced draft means must also 15 be regulated so that, upon a fall of the steam pressure from a predetermined degree, the same must be increased, or upon a rise in the steam pressure beyond a predetermined degree be decreased.

Many attempts have been made to regulate a furnace to obtain the desired efficiency of operation, all of which have failed in some feature, and, in the invention illustrated by 25 the accompanying drawings, I obtained the desired maximum efficiency in boiler operation by electrically connecting the damper flue, fuel supply means and forced draft means with suitable regulators that are sensitive to changes in the boiler condition and, 30 through means of the circuits hereinafter described, regulate the damper flue, fuel means and forced draft means as the condition of the furnace requires.

35 In the accompanying drawings, the numeral 7 designates a steam generating unit or furnace, which may be of any design or construction, having a fire box 8 provided with suitable fuel supply means, illustrated 40 in the present instance as an automatic stoker having an operating engine 9, a forced draft means 9' communicating with the ash pit 10 beneath the fire box by a duct 11, a chimney or flue 12 for carrying off the burnt 45 or exhausted gases and a steam header 13 having an outlet 14 for carrying the steam to the various desired points of consumption.

Connected at some point with the interior of the fire box 8 is a pipe or duct 15 which 50 communicates with the interior of a pontoon switch 16 consisting of a fluid container 17 having a central pan 18 therein forming an annular trough or channel 19 within the container for receiving a suitable fluid. The 55 pipe or duct 15 terminates in a valve 20, one end of which communicates with the inner chamber of the pontoon switch centrally of the pan 18, the handle 21 of the valve extending to an exterior point whereby the 60 sensitiveness of the regulation of the flue damper opening and the fuel feed by the draft within the fire box 8 may be controlled. Secured within the container 17 is an inverted pan or gas bell 22, the rim of 65 which projects into the fluid within the

channel 19 and centrally carried by the top of the gas bell in alignment with an aperture 23 in the top 24 of container 17 is a bracket member 25 to which is secured one end of a spring 26 having its upper end 70 secured to one end 27 of a bell crank lever 28.

The spring 26 is confined within a tube or cylinder 29 which covers opening 23 and into which projects bell crank lever end 27 75 through an elongated opening 30 in the wall thereof. Also confined within tube 29 is a second spring 31 having its lower end secured to end 27 of the bell crank lever and its upper end secured to an adjustable screw 80 32 carried by the cap 33 of the tube.

The lever 28 is pivotally secured at its apex between a bracket member 34 carried by a switch casing 35 which completely conceals said lever and the switch construction 85 now about to be described. The end 36 of lever 28 has two contacts 37 and 38 secured to opposite sides thereof adapted for electrical connection with contacts 39 and 40 respectively, carried by two spring contact 90 carrying members 41 and 42 secured at their lower ends as at 43 to the casing 35. Secured to the sides of the members 41 and 42 opposite the contacts 39 and 40 respectively are contacts 44 and 45 respectively, adapted 95 to be electrically connected with contacts 46 and 47 respectively, carried by the casing 35. The upper ends of levers 41 and 42 carry contacts 48 and 49 respectively, arranged for electrical connection with stationary contacts 100 50 and 51 respectively.

Positioned within the flue 12 is a damper or other regulating valve means 52 which may be of any desired construction, but in the present instance is illustrated as a plate 105 carried by a rotatably mounted shaft 53 one end of which is extended outwardly of the flue and carries a crank arm 54 adapted to be connected with a suitable control means by a rod 55. In this invention the rod 55 110 is connected with a suitable electric regulating device illustrated in Figures 1, 3 and 4 having a crank arm 56 carried by a shaft 57 driven from a motor 58. The drive shaft 59 of the motor extends into a gear reduction housing 69 and has a worm 61 mounted thereon which meshes with a worm wheel 62 carried by a shaft 63 which also carried a worm 64 meshing with a worm wheel 65 mounted on shaft 57. In order to limit the 115 movement of the lever 56 in either direction to open, or close damper 53, suitable limit switches 66 and 67 are provided which open the electrical circuit, to be later described, when the arm 56 reaches either of 120 its limits of movement.

The control member 68 of the furnace fuel supply means has a crank arm 69 carried by its operating shaft which is also connected by a rod 70 with a device similar 125

to that illustrated in Figure 3 and therefore further description thereof is deemed unnecessary. With this construction it will be readily obvious that a rotation of the 5 crank 56 of the device connected with the fuel supply means in one direction will increase the volume of fuel supplied the furnace and a rotation thereof in a reverse direction will decrease the volume of fuel 10 supplied the furnace. The motors 58 connected with the fuel supply means and the damper 52 are preferably simultaneously operated to decrease the volume of fuel supplied the furnace and the degree of opening 15 of the damper 52 upon the increase in the draft at the fire box 8 beyond a predetermined degree and to increase the volume of fuel supplied the furnace, and increase the degree of damper opening upon the draft 20 within the fire box falling below the predetermined degree. This is accomplished by connecting the motor 58 within a common circuit in which is included the switch mechanism illustrated in Figure 2.

25 In the diagram illustrated in Figure 6, 71 represents the series field of one motor 58, and 72 the armature, the field 71 having one end connected by a conductor 73 through a switch mechanism 74 with a positive line 75, the other end of the field 71 having a conductor 76 leading therefrom to the limit switches 66 and 67, limit switch 66 being connected with a conductor 77 which connects contact 48 with terminal 78 30 of a hand switch 79. Limit switch 67 is connected with contact 49 by a conductor 80 and with a contact 81 of a hand switch 82 by a conductor 83.

Contact 50 is connected with one end of a 40 resistance 84 by a conductor 85 and contact 51 is connected with one end of a resistance 86 by a conductor 87, the other end of resistance 84 and 86 being connected with a common conductor 88, in connection with a 45 negative service line 89 through switch 74, by conductors 90 and 91 respectively. Contacts 44, 45, 46 and 47 are connected with the conductors 85, 87, 90 and 91 respectively, whereby electrical connection of the 50 contacts 44 and 46 will cut out resistance 84, and electrical connection of contacts 45 and 47 will cut out resistance 86, for the reasons hereinafter set forth.

55 Contacts 39 and 40 are connected with the conductor 87 by a common conductor 92 and contacts 37 and 38 are connected by a common conductor 93 with a contact 94 of switch 79, the blade 95 of said switch which engages contact 94 when in its upper position being connected by a conductor 96 with a contact 97 of switch 82. The blade 98 of switch 82 which engages contact 97 when in its upper position is connected with the blade 99 of switch 79 through the armature 72, the other upper contact 100 of

switch 79 being connected with the other blade 101 of switch 82 by a conductor 102, and the upper contact 103 of switch 82 being connected with conductor 85 by a conductor 104. The lower contacts 105 and 106 of switches 79 and 82, respectively, are connected with the conductor 88 by a common conductor 107 and leading from contact 78 to blade 98 is a line 108 having therein a pilot light 109, and connecting 110 contacts 81 and blade 99 is a line 111 in which is positioned a pilot light 111.

Shunting across conductors 76 and 88 is a line 112 having therein a shunt field 113 which permits use of any type of motor, 80 i. e. motors of the series, compound or shunt type. When a series motor is employed, only field 71 is used and the shunt 113 is eliminated, when a shunt motor is used field 71 is eliminated and when a compound motor is used both the field 71 and the shunt 113 will be employed as will be readily obvious to those skilled in the art to which this invention appertains.

Positioned within the forced draft duct 90 11 is a control member 114, to the operating arm 115 of which a device similar to that disclosed in Figure 3 is connected by a rod 116. The motor of the forced draft controlling unit is controlled by a switch similar 95 to that disclosed in Figure 2 and actuated by means connected with the steam drum 13 or outlet 14 and sensitive to increase or decrease in the steam pressure to produce a corresponding adjustment of the forced 100 draft control means.

Secured within a casing 117 is a stationary cylinder 118 in which is reciprocally mounted a piston 119 having the upper-most 105 end of its piston rod secured in the upper end 120 of a yoke member 121 reciprocally mounted about the cylinder, the yoke being connected with the end 27 of switch bell crank lever 28 by a link 122 preferably pivotally carried by a part 123 carried by the extreme upper end of the piston rod and pivotally connected with the lever end 27 as at 124. In this form of my invention the bell crank lever 28 is normally urged to its intermediate or central position by a spring 125 110 secured as at 126 to the casing 117 and to an arm 127 carried by the bell crank lever.

The lower closed end of the cylinder 118 is connected by a pipe 128 with either the outlet 14 or the steam head 13 whereby a decrease in the generator steam pressure will permit an inward movement of the piston in the cylinder and an increase in the steam pressure will cause an outward movement of the piston. The device is adjusted so that 125 lever 28 will be held in its intermediate position at a predetermined steam pressure by weights 129 carried by a rod 130 suspended from the lower end of yoke 121.

From the foregoing description taken in 130

connection with the accompanying drawings it will be readily seen that the operation of a furnace equipped with my invention will be substantially as follows:—

5 Assuming that the condition of the furnace is at the desired point i. e. the steam pressure is at its predetermined degree and the draft through the fire box 8 is of the degree desired and the steam pressure then 10 falls below the set point. As the steam pressure decreases, piston 119 moves inwardly swinging switch arm 36 to the left, Figures 2 and 5, electrically connecting contacts 37 and 39. At this point the current flows 15 through field 71, divides at limit switches 66 and 67 and passes through resistance 84 and 86 to conductor 88 and out through line 89 and the motor 58 for actuating the forced draft control means remains inoperative. A 20 further fall of the steam pressure causes a continued inward movement of the piston until contacts 48 and 50 are broken, thus causing the current to flow through field 71, conductor 76, limit switch 67, contacts 49 and 25 51, where the current is again divided and part of it flowing through resistance 86 and out through line 89 and conductor 88 and the rest through conductor 92, contacts 39 and 37, conductor 93, switch blade 95, conductor 30 96, switch blade 98, armature 72, switch blade 99, conductor 102, switch blade 101, conductor 104, conductor 85, resistance 84, conductor 90 and then through conductor 88 to line 89. With the parts in this position 35 the motor 58 controlling the forced draft means operates at slow speed.

With the forced draft actuating motor operating at slow speed pilot light 111 will burn at half brilliancy by reason of the current passing through line 83, conductor 110, knife blade 99, conductor 102, knife blade 101, conductor 104, conductor 85, resistance 84, conductor 88 and out through line 89. A continued fall in the steam pressure electrically connects contacts 44 and 46 when resistance 84 is cut out and the motor runs at full speed until limit switch 67 is actuated to open the circuit. With the resistance 84 cut out, pilot light 111 will burn at full 50 brilliancy as will be readily apparent.

As the steam within the generator increases, the piston 119 is urged outwardly to return the switch parts to normal position and should the pressure exceed the set degree, contacts 38 and 40 will be closed when the flow of current is substantially the same as that first described. A continued rise in the steam pressure causes contacts 51 and 49 to be disconnected when the division of 60 the current is then through limit switch 66, contacts 48 and 50, conductor 85, conductor 104, switch blade 101, conductor 102, switch blade 99, armature 72, switch blade 98, conductor 96, switch blade 95, conductor 93, contacts 38 and 40, conductor 92, conductor 87,

resistance 86, conductor 91, conductor 88, and out through line 89, the motor is then running at slow speed to close force draft control member 114. The other division of the current with parts in the condition just 70 described is through limit switch 66, conductor 77, conductor 108 and consequently pilot light 109, switch blade 98, conductor 96, switch blade 95, conductor 93, contacts 38 and 40, conductor 92, conductor 87, resistance 86, conductor 91, conductor 88 and out through line 89, the pilot light 109 thus burning at half brilliancy.

Should the steam pressure continue to rise 80 the contacts 45 and 47 will be electrically connected to cut out resistance 86 and drive the motor 58 at full speed, until the limit switch is actuated, and also to burn the pilot light 109 at full brilliancy. The object of having conductors 92 and 93 electrically disconnected when the operating switch is in normal position, is to eliminate 85 any possibility of creepage of the motor should the contacts 48 and 50, and 51 and 49 become dirty or one afford more resistance to the flow of current than the other as will be readily apparent. With this arrangement of the circuits a powerful dynamic braking effect is also produced as when contacts 48 and 50, and 49 and 51, respectively are connected, the armature is short circuited and consequently immediately 90 stopped.

When the draft within the fire box 8 falls 100 below the set degree, the gas bell 22 is permitted an upward movement to permit contacting of contacts 38 and 40 of the switch mechanism connected therewith, or in the event the gas suction increases beyond the desired degree, the movement thereof is reversed, and as the operation of the switch mechanism and the various electrical circuits, described in connection with the forced draft regulating device, is identical with the damper regulator and feed control, further 105 description is deemed unnecessary.

For the purpose of disconnecting the automatic control feature, hand switches 79 and 82 are employed as will be readily appreciated. The hand switches 79 and 82 are 110 primarily for operating the regulating devices independent of the pontoon switch 16 and the steam controlled device.

What I claim as my invention is:

1. In a furnace, regulating means therefore including an electric motor, an electric circuit including said motor, means within said circuit for actuating said motor upon a change in the furnace condition from normal, and means within the circuit whereby 115 a strong dynamic braking force is applied to said motor upon the furnace condition returning to normal.

2. In a furnace, regulating means therefore including an electrical device, an elec- 120

- tric circuit including said device, means within said circuit for automatically actuating said device upon the furnace condition changing from normal, and means within 5 the circuit for permitting manual manipulation of said device.
3. In a furnace, regulating means therefor including an electrical device, an electrical circuit including said device, means 10 within said circuit for automatically actuating said device upon a change in the furnace condition from a predetermined condition, and means permitting the actuation of said device independently of said automatic 15 means.
4. In a furnace having a fire chamber, means for feeding fuel to the fire chamber, forced draft means connectible with the fire chamber and steam outlet, of an electric motor 20 connected with said fuel feeding means to control the same, an electric motor connected with said forced draft means to control the same, a circuit making and breaking device, circuits including said circuit making 25 and breaking device and said fuel feeding control motor and forced draft means controlling motor, and means actuated by the pressure at said steam outlet for operating said circuit making and breaking device, whereby the adjustment of said fuel 30 feeding means and said forced draft means is coordinated with the pressure at said steam outlet.
5. In a furnace having a fire chamber, means for feeding fuel to the fire chamber, 35 forced draft means connectible with the fire chamber, a flue damper and a steam outlet, of an electric motor connected with said fuel feeding means to control the same, an electric motor connected with said forced draft 40 means to control the same, an electric motor connected with said flue damper to control the same, a circuit making and breaking device, circuits including said circuit making and breaking device and said fuel 45 feeding control motor and forced draft means control motor, means actuated by the pressure at said circuit making and breaking device, whereby the operation of said fuel feeding means and said forced draft 50 means is coordinated with the pressure at said steam outlet, a second circuit making and breaking device, a circuit including said circuit making and breaking device and said flue damper control motor, and means 55 actuated by the pressure within said fire chamber for operating said second circuit making and breaking device, whereby the adjustment of said flue damper is coordinated with the pressure in the fire chamber 60 and consequently with the operation of said fuel feeding means and said forced draft means.

In testimony whereof, I affix my signature.

WILMER M. SHALLCROSS.
